UNITED STATES PATENT OFFICE.

MAJOR DANE PORTER, OF LEWISTON, NEW YORK.

CONTAINER.

No. 916,485.

Specification of Letters Patent. Patented March 30, 1909.

Application filed May 5, 1908. Serial No. 430,943.

To all whom it may concern.

Be it known that I, MAJOR DANE PORTER, a citizen of Canada, and a resident of Lewiston, in the county of Niagara and State of New York, have invented certain new and useful Improvements in Containers, of which the following is a specification.

My invention relates to containers made of wood pulp, or similar plastic material, and its novelty consists in the means employed whereby the container may be opened after having been sealed.

In the drawings, Figure 1 is a central vertical section of a container embodying my invention; Fig. 2 is a similar view on a smaller scale of a different form of container, and Fig. 3 is a plan view of the severing or rupturing cord or wire.

In Fig. 1 of the drawings, 10 is a container in the shape of a squat wide mouthed bottle made of wood pulp, or similar plastic material. It is restricted at 11 to form a neck 12 terminating in a mouth 14 and is provided with a cork or stopper 13. This latter fits snugly against the inner surface of the mouth 14 and after the contents of the bottle are in place is preferably secured in its position by glue or cement so that it can not be removed.

In Fig. 2, I have shown a slightly modified form, the neck being omitted and the stopper 130 inserted directly into the cylindrical body 100. The cord or wire 150 is also inserted in the body.

In the process of forming the container a cord or wire 15 is wound around the neck of the same in several turns. Preferably the innermost turn is nearest the inner surface of the container and the outermost turn terminates beyond the surface of the container.

It will be noticed that the bottom of the container is made of a different piece from the body. This construction enables the stopper 13 to be inserted after the body is formed and then, if desired, the container is filled when arranged in an inverted position and the bottom is secured in place afterward.

However the container is filled and sealed, when it has once been closed it is practically an integral structure without an opening. When now it is desired to open the container the cord or wire 15 is seized by its projecting end and is unwound. Each turn as it is unwound interrupts the continuity of the surface in which it is embedded and finally ruptures the structure so that the stopper and the mouth of the container above that point may readily be removed.

What I claim as new is:

1. A container made of plastic material and provided with a cord, or wire, embedded in its structure in a plurality of turns, so that the container is destroyed by the unwinding of the cord or wire. 60

2. A container having an open top, a stopper adapted to be secured therein and a cord embedded in the container by a plurality of turns below the stopper. 65

3. A container having a cord, or wire, embedded in its substance and made substantially integral therewith, the cord or wire being wound in surfaces substantially concentric with the cross sectional contour of the container. 70

4. A container having a cord, or wire, embedded therein and made integral, the cord or wire being wound so that its successive turns are arranged in different planes, each of which is at an angle to the longitudinal axis of the container. 75

5. A container having an open top, a stopper adapted to be secured therein and a cord embedded in the container by a plurality of turns below the stopper, the innermost turn being nearest the stopper. 80

Witness my hand this 28th day of April, 1908, at Lewiston in the county of Niagara and State of New York.

MAJOR DANE PORTER.

Witnesses:

ALFRED N. ROBBINS,
ERNEST E. YOWELL.
